UNITED STATES PATENT OFFICE.

MERLE BUCKER, OF CHICAGO, ILLINOIS.

CARBURETER.

1,168,782.

Specification of Letters Patent. Patented Jan. 18, 1916.

Application filed January 15, 1912. Serial No. 671,331.

To all whom it may concern:

Be it known that I, MERLE BUCKER, a citizen of the United States, residing at Chicago, county of Cook, and State of Illinois, have invented certain new and useful Improvements in Carbureters, of which the following is a specification.

The present invention relates to carbureters for use in vaporizing liquid fuels for operating internal combustion engines, and the objects of the invention are (1) to provide a device which will mix the liquid fuel and air to as perfect a gas as possible; (2) to provide a regulation of air and fuel which will maintain an explosive mixture unvaried by the various speeds of the engine from the lowest to the highest, either under throttle control or by reasons of variations of load; (3) to provide an adjustment according to temperature, atmosphere or grade of fuel which, when once made, will suffice for all speeds of the engine; (4) to provide for the heating of the fuel between its point of regulation and its point of discharge into the mixing chamber; and (5) to provide a device which shall be simple in construction and efficient and economical of fuel in operation.

These several objects are attained in the two embodiments of my invention described in the following detailed description and illustrated in the accompanying drawing, while the scope of the invention is pointed out in the appended claims.

In the drawing, Figures 1 to 6, inclusive, illustrate the first form of the invention, and Figs. 7 to 11, inclusive, the second. Fig. 1 is a central vertical section of the carbureter constituting the first embodiment; Fig. 2 is a section taken on a plane indicated by the line 2—2 of Fig. 1, illustrating the mechanism for controlling the auxiliary air inlet; Fig. 3 is a central section of this latter mechanism similar to that shown in Fig. 4, but illustrating the piston valve in its uppermost position; Fig. 4 is a side elevation of said mechanism for regulating the auxiliary air inlet; Fig. 5 is a central vertical section of the carbureter of Fig. 1, taken on a plane at right angles to that of the section of Fig. 1; and Fig. 6 is a horizontal section taken on a plane indicated by the line 6—6 of Fig. 5, illustrating particularly the liquid fuel passages; Fig. 7 is a central vertical section of the carbureter constituting

the second form of my invention; Fig. 8 is a transverse section taken on a plane indicated by the line 10—10 of Fig. 7, illustrating the mechanism for controlling the secondary air inlet; Fig. 9 is a bottom view of the second form of the invention, parts being broken away and parts shown in section; Fig. 10 is a central vertical section of the carbureter constituting the second form of the invention taken on a plane at right angles to the plane of section of Fig. 7; and Fig. 11 is a horizontal section of this form of the invention taken on a plane indicated by the line 13—13 of Fig. 10.

Throughout these several figures, like characters refer to like parts.

In the form of the invention illustrated in Figs. 1 to 6, inclusive, 10 designates the body of the carbureter, which is provided with a mixing chamber 11, adapted to be placed in communication with an engine to be supplied through a passage 12 and having a main air inlet controlled by a valve 13, an auxiliary air inlet controlled by a piston valve 14, and a liquid fuel supply controlled by a taper valve 15. The body is provided with inner and outer walls which form a heating jacket 16, which may be supplied with hot water, gas or the equivalent for the purpose of heating the liquid fuel on its passage to the mixing chamber 11. Suitable threaded openings 100 and 101 are provided for connecting the jacket 16 with a suitable source of such heating fluid. A liquid fuel reservoir 17 is located adjacent to the body 10 and in direct communication with the fuel passages. A float 18 is used in conjunction with a valve 19 to maintain a constant level of fuel in the chamber 17.

The main air inlet is provided by the annular passage 20 between the main air valve 13 and the adjacent portions 21 of the wall of the mixing chamber 11. The liquid fuel inlets to the chamber 11 are provided by an annular series of passages 22 communicating directly with the annular air inlet 20. The float 18 maintains the level of the fuel at approximately the height of the discharge ends of these inlets 22. From this it will be seen that as the valve 13 is raised, air will rush through the passage 20, by reason of the suction of the engine, and the fuel fed through the fuel inlets 22 will be taken up and carried into the chamber 11 where it

95

100

105

110

will be thoroughly mixed with the air as it is drawn through the passage 12 into the engine cylinder, or cylinders.

An important feature of my invention is the taper valve 15, which is directly connected to the valve 13 and regulates the flow of fuel according to the position of the latter valve. This is accomplished by giving the valve 15 a taper which will best suit the conditions of operation of the particular engine with which the carbureter is to be used. This tapered portion of the valve opens or closes more or less of the passage 23 extending between the dash-pot 24 and the cross-channel 25. The latter channel communicates with the annular channel 26, from which the passages or inlets 22 extend upwardly to their discharge points. In operation, heat is applied to the fuel as it passes through these passages 22 by the heating fluid contained in the heating jacket 16. A passage 27 connects the dash-pot with the outlet 28 of the fuel reservoir 17. The dash-pot piston 29 is preferably located also upon an extension of the main stem 30, which is tapered, as illustrated, to provide the taper valve 15. This latter stem also carries the main air valve 13. By this construction, the dash-pot retards the to-and-from movements of the stem 30 and its connected parts and provides a steadier action under the suction of the engine. After the annular channel 26 is routed out, it is closed by the annular plate 31. The channel 25 is located in a portion 32 of the casting which bridges the main air opening 33. A boss 34, projecting downward from this bridge, is threaded at its lower end for the reception of the dash-pot 24. A cap 35 closes the lower end of the dash-pot, and a boss 36 upon the latter is threaded for the engagement of the outlet connection 28.

A tubular guide 37 is formed integral with the bridge 32 and extends upward from it. It is adapted to pass inside the hollow top-shaped valve 13 and to engage the lower edges of the latter to guide its movement. A bushing 38 is located within the guide 37 and closely engages the stem 30, but leaves the latter free to reciprocate within it. The upper end of the valve 13 is threaded upon the lower end of the sleeve 39 surrounding the stem 30. The upper end of this sleeve is secured to the piston valve 40 which coöperates with the slot 41 in controlling the admission of auxiliary air to the chamber 11. This piston reciprocates within the cylinder 42 in which the slot 41 is located. The stem 30 is threaded through a threaded opening in the sleeve 39 and is provided at its upper end with a transverse slot for the engagement of a screw-driver to adjust it, and consequently the taper valve 15, with reference to the

main air valve 13 and the auxiliary air valve 40. As illustrated, the stem 30 is reduced in diameter below the threads which engage the sleeve 39. This is to allow for assembling. The cylinder 42 is threaded at its lower end into a cap 43 which is in turn threaded into the upper end of the casting forming the body 10. This leaves the portion of the cylinder 42, which lies below the piston valve 40, in direct connection with the chamber 11. As the valves 13 and 40 are moved upward in response to the suction of the engine, more or less air is admitted through the slot below the piston. The greater the upward movement, the greater the amount of air admitted. This will be apparent from a consideration of Figs. 1 and 3 where the parts are shown in different positions, the former with the air-supply cut off and the latter with the slot considerably opened. In this way, the valve 40 operates to vary the vertical dimension of the auxiliary air inlet. A covering sleeve 44 surrounds the cylinder 42 and may be rotated by a handle 45. In its rotation, it rides upon the upper face of the collar 46, threaded upon the exterior of the lower end of the cylinder 42. A projection 102 overhangs the slight flange at the lower end of the sleeve 44 to prevent its being lifted from engagement with the collar 46. The sleeve 44 is also provided with a vertical slot 47 which is positioned to register more or less with the slot 41 in accordance with the movements of the handle 45. Normally, these slots 41 and 47 preferably overlap each other about half way, as illustrated in Fig. 2. By this arrangement, it will be seen that the available width of the slot 41 may be varied. Thus the piston valve 40 in its operation varies the available length of the slot 41 in accordance with the operation of the engine, while the sleeve 44 varies the available width of said slot in response to the operation of handle 45. The former permits an admission of air corresponding to the engine requirements. The latter is used to regulate the admission of air in accordance with temperature, atmospheric and fuel conditions. In operation, the sleeve 44 is set and the best operation of the engine at various speeds is obtained by shaping and adjusting the taper valve 15, and advancing the time of opening of piston valve 40 with relation to the lower edge of port 47, leaving a set opening through that passage which may be later closed to compensate for leakage of air by wear of engine, valve stems or carbureter. When once set, the sleeve 44 need not be changed again until a change in the grade of fuel, or in the temperature, or atmosphere, require it. When set to obtain the best results at one speed of the engine, the elements operated

in response to the suction of the engine will take care of the regulation of fuel and air for all other speeds.

By means of the collar 46, the point at which the piston valve 40 begins to admit auxiliary air to the chamber 11 may be carefully adjusted. This adjustment may be made from time to time to compensate for leakage of air at other points in the carbureter, or in the engine. This adjustment alone will suffice for the ordinary conditions of wear. In this form of the invention, a cap 48 is screwed on to the top of the cylinder 42 and a coiled compression spring 49 bears between it and the piston valve 40. A set screw 50 is threaded into the cap 48 so as to set the stem 30 against movement. This is to be used when the carbureter is employed in operating engines carrying a set load. In other cases, the set screw 50 is kept free from the stem 30 so that the latter may reciprocate under the action of the engine and the restoring spring 49. In some instances, the spring 49 may be omitted and the weight of the stem and connected parts relied upon to restore it when the suction of the engine drops off.

The passage 12 is provided with a butterfly valve 51 by which the effect of the suction of the engine upon the valve 13 may be regulated. This valve is operated by a suitable lever like the lever 106 of the second form of this invention. A flange 52, provided with openings 53, is arranged for the connection of the carbureter to the engine. In supplying fuel to the carbureter, the fuel supply pipe is connected to the threaded projection 54 which is provided with a passage adapted to communicate with the reservoir 17. This projection is also provided with a valve seat which co-operates with the valve 19 in the control of the supply fuel to the reservoir. This control is brought about automatically by the float 18 which is secured to one end of the lever 55, which is pivoted at an intermediate point 56 and embraces the stem 57 of the valve 19 at its opposite end. This stem is provided with a knurled head 58 for convenience in adjusting it with respect to the sleeve 59 into which it is threaded. This sleeve is, in turn, provided with a knurled head 60 for convenience in this adjustment. This sleeve is slidably mounted within a sleeve 61, which is threaded at its lower end into engagement with the cap plate 62 of the reservoir 17. In operation, as the fuel passes out of the reservoir, the float settles and, as it settles, the outer end of the lever 55 engages the sleeve 59 and carries it and the valve stem upward, thereby opening the valve to allow fuel to pass into the reservoir. As the latter is filled, the float 18 rises and the outer end of the lever 55 moves downward, allowing the valve to close by its own weight to

cut off the further supply of fuel, and finally, by engaging the collar on the valve 19, exerts a pressure to keep the valve closed more tightly.

In the operation of the carbureter proper, the suction of the engine raises the main air valve 13 and air is admitted through the main air inlet 20 into the chamber 11. As it rushes through this annular opening 20, it draws out fuel from the fuel passages 22 and vaporizes it and mixes it thoroughly with the air. This same upward movement of the valve 13 admits auxiliary air through the slots 47 and 41 in accordance with the position of the piston valve 40. In this operation, the amount of fuel admitted is regulated by the taper of the taper valve 15 and by the adjustment of the auxiliary air mechanism. It will be seen that variations in the amount of auxiliary air admitted will vary the lifting action upon valve 13 and consequently the amount of air admitted to chamber 11 through inlet 20 and the amount of fuel allowed to pass taper valve 15. The more the auxiliary air admitted, the less will be the lift of the valve 13 and the less the admission of air through inlet 20 and of fuel past the taper valve 15 and vice versa. In each case, the variation of fuel admission will depend, of course, upon the particular taper of the taper valve. In practice, this taper is made to provide the best results for a given make of engine and the collar 46 will be adjusted so that the auxiliary air port will be slightly open when the engine is barely turned over. In reaching these results, the stem 30 will, of course, be adjusted to bring the action of the taper valve into play at the right point in the movement of the parts. With the mechanism thus adjusted, it only remains to shift the sleeve 44 to regulate the auxiliary air inlet, according to atmospheric changes and changes in temperature or grade of fuel.

In the second form of the invention, illustrated in Figs. 7 to 11, inclusive, the general arrangement of mixing chamber and fuel and air inlets and control valves is the same as heretofore described. In this form of the invention, the restoration of the valves to normal is dependent upon the weight of the parts, the spring 29 of the previous form being omitted; the fuel reservoir has the form of an annular chamber surrounding parts of the carbureter structure instead of being separate and distinct from the latter; and the fuel passes downward past the taper valve on its way to the mixing chamber, instead of upward as in the previous form. In this form of the invention, the body 10' is provided with a central mixing chamber 11' surrounded by a water-jacket 16', having threaded openings 100' and 101' for connection with some suitable source of hot gas, water or other fluid. The chamber 11' com-

municates with the engine through a passage 12' controlled by the butterfly valve 51 operable by lever 106, as before. The chamber 11' is closed by a cap 43' into which the slotted cylinder 42' is screwed. The covering sleeve 44' rides, as before, upon a collar 46' and is prevented from being lifted out of engagement with it by a projection 102'. It is similarly provided with a handle 45'.
10 A cap 48' closes the upper end of this sleeve. The piston valve 14' is secured, as before, to a sleeve 39', which carries the main air valve 13' at its lower end. In this case, the stem 30', which is screw-threaded into the upper end of the sleeve 39', is provided with a T-shaped opening 103' by which air is admitted to the interior of the sleeve 39'. And openings 104' place the interior of this sleeve in communication with the interior of the main air valve 13'. Thus, in this form of the invention, air at atmospheric pressure is supplied to the interior of the latter valve at all times. This will prevent any suction created within the valve 13' from drawing fuel from the passage 105' up into the interior of the valve 13' around the stem 30'. In this form of the invention, the reservoir 17' is provided by a casting which fits against the under face of the body 10' and provides the lower walls of the mixing chamber 11'. This casting is provided with a central opening 33' for the admission of air to the annular air inlet 20'. This opening 33' is spanned by a bridge 32', containing the transverse channels 105' and 25', united by a small opening with which the taper valve 15', formed upon the stem 30', co-operates in regulating the flow of fuel from the reservoir 17' to the fuel outlet passages 22', the course of the fuel being from the reservoir 17', through channel 105', thence past the taper valve, thence through channel 25', annular channel 26', and the outlet passages 22'.
15 As before, the annular channel 26' is closed by a plate 31'. The upper side of the bridge 32' is provided with a tubular guide 37' into which the bushing 38' is fitted, just as in the previous form. A boss 34' is also provided on the under side of the bridge 32' for the reception of the dash-pot 24', which is provided with a cap 35' and a piston 29', just as in the previous form. The mechanism for controlling the admission of fuel to the reservoir is the same as that of the previous figure, and the various parts are indicated in the drawing by the same reference characters, except that the cap plate 62' replaces the somewhat differently shaped cap plate 62 of the first form.
20 In the operation of this form of the invention, the admission of air at the main and auxiliary ports and of fuel at the fuel ports is the same as in the case of the previous form, except that in the present form a

return spring is not provided for returning the parts to normal. The same permanent adjustments may be made to meet the requirements of the engine and the same variable adjustments may be made to meet changing conditions of atmosphere, temperature and grade of fuel. It will be noted, however, that in this form of the invention, there is no application of heat to the fuel after it has passed the taper valve 75 and before it emerges into the mixing chamber, as was the case in the first form of the invention.

Although I have illustrated two embodiments of my invention, it will be apparent that many other changes and alterations than those suggested by these forms may be made without departing from the spirit and scope of the invention. I, therefore, do not wish to be limited to the specific forms here illustrated, but aim to cover all such changes and alterations by the terms of the appended claims.

What I claim as new and desire to secure by Letters Patent of the United States is:—

1. A carbureter comprising a chamber adapted to communicate with an engine to be supplied, said chamber having a central opening in its bottom wall, a central air valve for substantially closing said opening and providing an annular air inlet passage between its outer surface and the inner faces of the adjacent chamber walls, means for guiding said valve in its movements independently of said chamber walls, liquid fuel inlets extending through said adjacent chamber walls and opening into said air inlet passage, a fuel supply passage leading to said fuel inlets, and a taper valve for regulating the supply of fuel to said fuel inlets in accordance with the operation of said air valve.

2. A carbureter comprising a chamber adapted to communicate with an engine to be supplied, said chamber having a central opening in its bottom wall, a central air valve movable downward to substantially close said opening by engaging inwardly projecting portions of the side walls of said chamber, said valve and projecting portions forming an annular air inlet passage between them, means for guiding said valve in its movements independently of said chamber walls, liquid fuel inlets extending through said side walls into communication with said annular air inlet, a supply passage to said inlets having a portion directly beneath said central valve, and a taper valve located in said portion of said passage and operative to regulate the supply of fuel to said fuel inlets in accordance with the operation of said air valve.

3. A carbureter comprising a chamber adapted to communicate with an engine to be supplied, said chamber having a central

opening in its bottom wall, a central air valve for substantially closing said opening and providing an annular air inlet passage between its outer surface and the inner 5 faces of the adjacent chamber walls, means for guiding said valve in its movements independently of said chamber walls, liquid fuel inlets extending through said adjacent chamber walls and opening into said air inlet passage, a fuel supply passage leading to said fuel inlets, a taper valve for regulating the supply of fuel to said fuel inlets in accordance with the operation of said air valve, and a heating jacket surrounding that 10 portion of said chamber walls through which said inlets extend.

4. A carbureter comprising a chamber adapted to communicate with an engine to be supplied, said chamber having a central 15 opening in its bottom wall, a central air valve movable downward to substantially close said opening by engaging inwardly projecting portions of the side walls of said chamber, said valve and projecting portions 20 forming an annular air inlet passage between them, means for guiding said valve in its movements independently of said chamber walls, liquid fuel inlets extending through said side walls into communication 25 with said annular air inlet, a supply passage to said inlets having a portion directly beneath said central valve, a taper valve located in said portion of said passage and operative to regulate the supply of fuel to 30 said fuel inlets in accordance with the operation of said air valve, and a heating jacket surrounding that portion of said chamber walls through which said inlets extend.

40 5. A carbureter comprising a casing having a chamber adapted to communicate with an engine to be supplied and a central vertical passage for supplying air to said chamber from beneath, a vertical guide secured 45 at its lower end to said casing and extending upward in said vertical passage, a central vertically movable suction-operated valve fitted over the upper end of said guide and guided thereon in its to-and-fro vertical 50 movements, portions of the peripheral walls of said casing extending inwardly into the path of movement of said valve and forming a coöperating valve seat therefor outwardly of said valve, a plurality of liquid fuel inlets in said valve seat in position to be substantially closed by said valve when the latter is in its lowermost position, a fuel supply passage for said fuel inlets traversing portions of said casing, and a taper valve secured to said first mentioned valve and extending down through said guide into coöoperative relation with the walls of the supply passage therein to vary the flow of 60 fuel through said passage.

55

the latter is in its lowermost position, and a fuel supply passage in the body of the casing leading to said fuel inlets.

6. A carbureter comprising a casing having a chamber adapted to communicate with an engine to be supplied and a central vertical passage for supplying air to said chamber from beneath, a vertical guide secured at its lower end to said casing and extending upward in said vertical passage, a central vertically movable suction-operated valve fitted over the upper end of said guide and guided thereon in its to-and-fro vertical movements, portions of the peripheral walls of said casing extending inwardly into the path of movement of said valve and forming a coöperating valve seat therefor outwardly of said valve, a plurality of liquid fuel inlets in said valve seat in position to be substantially closed by said valve when the latter is in its lowermost position, a fuel supply passage in the body of the casing leading to said fuel inlets, and means for regulating the amount of fuel issuing from 70 said inlets.

7. A carbureter comprising a casing having a chamber adapted to communicate with an engine to be supplied and a central vertical passage for supplying air to said chamber from beneath, a vertical guide secured at its lower end to said casing and extending upward in said vertical passage, a central vertically movable suction-operated valve fitted over the upper end of said guide and guided thereon in its to-and-fro vertical movements, portions of the peripheral walls of said casing extending inwardly into the path of movement of said valve and forming a coöperating valve seat therefor outwardly of said valve, a plurality of liquid fuel inlets in said valve seat in position to be substantially closed by said valve when the latter is in its lowermost position, a fuel supply passage for said fuel inlets traversing portions of said casing, and a taper valve secured to said first mentioned valve and extending down through said guide into coöoperative relation with the walls of the supply passage therein to vary the flow of 80 fuel through said passage.

In witness whereof, I hereunto subscribe my name this 13th day of January, 1912.

MERLE BUCKER.
